UNITED STATES PATENT OFFICE

JAMES D. COLE, OF CLEVELAND HEIGHTS, OHIO, ASSIGNEE TO THE DOMESTIC ELECTRIC COMPANY, OF CLEVELAND, OHIO, A CORPORATION OF OHIO

EXERCISER MECHANISM

Application filed October 29, 1928. Serial No. 315,858.

This invention is concerned with mechanism for imparting vibratory movement to parts of the human body, and as shown is particularly adapted to vibrate a flexible strap, the strap being in embracing contact with whatever part of the body it is desired to massage, and the vibratory movement being imparted to the strap by alternately pulling the ends thereof.

10 The essential object is to provide a strap vibrating mechanism which will be simple to construct, effective in operation and of comparatively light weight.

A further object is to provide an improved 15 and simplified driving arrangement between a strap to be vibrated and an electric motor.

A further object is to provide a strap vibrating mechanism in which all parts of the mechanism may be easily and quickly assembled, and which, though comparatively light 20 in weight, will be adequately strong to withstand continued shock due to the vibrating impulses under load.

A further object is to provide a support 25 for a vibrating mechanism, by which the mechanism may be easily and firmly attached to existing parts of a dwelling house without modification of such parts.

Further objects and features will become 30 apparent from the following description relating to the accompanying drawings, which show the preferred forms of the invention. The essential characteristics are summarized in the claims.

35 In the drawings, Fig. 1 is a sectional side elevation of the machine, the motor and gearing housing being shown in substantial 40 by the line 2—2 on Fig. 1; Fig. 2 is a horizontal sectional plan, as indicated 45 by the line 2—2 on Fig. 1; Fig. 3 is a side elevation of the machine with a modified form of supporting device; Fig. 4 is a plan view of the supporting device shown in Fig. 3 as applied to a door stile or frame member; Fig. 5 is a side elevation showing still another form of supporting device, and Fig. 6 is a fragmentary sectional plan view taken along the line 6—6 on Fig. 5.

Referring in detail to the drawings, 1 indicates the general housing for the motor and

vibrator gearing. The housing, as shown, comprises two hollow sections, preferably castings, there being a section 2 and a section 3 suitably secured together by means of studs 4 (see particularly Fig. 2). The studs 5 are threaded into the section 2 as at 5 and project through openings in the end wall of the section 3, the projections being threaded and engaged by cap nuts 6 bearing against such wall of the housing. The studs 4 incidentally support the field F of the motor, the field frame being perforated to receive the studs, as shown in Fig. 2, and there being field frame positioning nuts and spacers respectively designated 7 and 8 carried on the studs and engaging the field frame to hold the frame in longitudinally fixed position within the housing. The motor has the usual armature A, brushes B and commutator C.

The housing section 2 has projecting from one end a hollow housing portion 10 which carries a bushing 11 near the top thereof and which forms the bearing for one end of the armature shaft 12 having a worm formation 13 thereon as at 13. In addition to the bushing bearing 11, the motor shaft has a bushing bearing at 27 supported by a central extension of the housing section 3. Suitable shaft end positioning threaded members 28 in the bushing 11 and a cap member 29 respectively prevent excessive longitudinal movement of the motor shaft.

Below the bushing 11 and extending transversely of the hollow housing portion 10 is a shaft 14 carrying a worm gear 15 meshing with the worm formation 13 and suitably attached to the shaft as by a set screw 15a. By reason of the gearing, the shaft 14 is driven at reduced speed with relation to the motor shaft. The shaft 14 is supported by a lateral extension 16 forming part of the housing projection 10, and by a removable cap member 17 forming a side closure for the housing portion 10 and carrying a lateral bored-out projection 18 opposite the housing projection 16.

Suitable means for controlling the motor may comprise a snap switch S supported, as shown in Fig. 1, on the top side of the motor

casing section 2. The motor shaft may be lubricated at one end by means of a felt washer 30 seated in the member 29, there being an oil hole 31 above the washer, and at the other end by grease placed in the worm gear containing portion of the hollow housing extension 10 as through a removable closure member 33.

10 The ends of the shaft 14 project beyond the housing and cap extensions 16 and 18 and carry rigid therewith disc-like members 20 having hub portions 20a fitting over the respective shaft ends and secured thereto as by set screws 21. As suggested in Fig. 3, each disc has a plurality of threaded openings, designated 22, positioned various distances from the axis of the shaft 14.

15 The openings in the disc members 20 may be of any convenient number to secure the desired variety of vibrating impulse lengths to a strap 23 which has its ends secured to threaded pins 24 adjustably positioned relative to the discs by reason of the plurality of threaded openings. Each pin is threaded on its inner end to engage a selected threaded opening 22 and has a cylindrical portion 24a for engaging the respective end of the strap and an enlargement beyond the cylindrical portion to serve as a finger piece and to overlie the adjacent portions of the strap to hold the strap on the pin. The strap ends, as shown in Figs. 2 and 3, comprise comparatively heavy end members 25, preferably leather, which have key-hole shaped openings 26, the restricted portions of the key-hole shaped openings embracing the pin portions 24a.

20 It will be understood that the threaded openings 22 opposite those shown in Fig. 3 are so related to the openings shown in Fig. 3 that the two pins placed in any corresponding pair of openings will be diametrically opposed to each other and spaced equally from the shaft axis. Thus, the vibrating impulses at the two ends of the strap will be of equal length for a given setting, this length being adjustable by resetting the pins.

25 The vibrating mechanism supporting device, as shown in Figs. 1 and 2, comprises a bracket 35 formed at one end to underlie the motor housing and being secured thereto as by means of screws 36, the other end of the bracket being adapted to overlie a window sill or like building part, such as diagrammatically indicated at W, the extreme end of the bracket being turned down to provide a hook effect at 37 for engaging the abrupt surface outwardly from the sill, against which the window sash is normally positioned when closed. Rising from the hollow portion of the bracket is an ear 38 which supports a suitable clamping screw 39 having a shoe 40 for engaging the window sash W2, shown slightly raised. The clamping shoe, as well as the bracket, may carry suitable

padding 41 and 42 for engaging the window sill and sash respectively.

With the vibrating mechanism supported by the above described device, continued vibration may be imparted to the strap under load without likelihood of the mechanism coming loose or marring the building. 70

75 In Figs. 3 and 4 is shown a modified arrangement for securing the vibrating mechanism to a door or like building part. This comprises a U-shaped bracket 50 having substantially parallel arms 52 and 53 for embracing opposite sides of the usual door stile. The arm 52 carries a clamping screw and plate 54 and the arm 53 is turned inwardly 80 at its end at 55 to engage the inner edge of the stile adjacent the panel to prevent outward movement of the securing means in case the screw should become loosened.

85 Dwelling house door stiles vary but slightly in width (from panel to door edge) and I find that, in the proportions shown, the turned in part 55 usually engages in the inner edge of the stile with adequate clearance between the door edge and the cross portion of 90 the bracket. The strap vibrating mechanism may be supported by an outwardly bent ear 56 arranged to supportingly underlie the motor housing and to be secured thereto as described in connection with the support 95 shown in the earlier figures.

95 A still different form of mounting is shown in Figs. 5 and 6. In these figures, the attaching device for doors is shown as a forked bracket 60, the base of the fork being suitably extended as at 61 to support the motor housing. The arms of the fork embrace the door stile and each has a downwardly open slot 62 adapted to embrace the usual shaft D to which the two door knobs are secured. Each slot may be rearwardly recessed as at 63 so as to positively prevent vertical movement of the fork with relation to the door. 100

105 A suitable clamping arrangement may comprise a clamping plate 64 urged inwardly as by a screw 65 having a thumb piece 66, the plate 64 being arranged to engage the edge of the door and draw the fork forwardly, pulling the recesses 63 into tight engagement 110 with the door knob shaft. It may be assumed that in using the supporting arrangements shown in Figs. 3 to 6 the door may, if desired, be held ajar as by means of a wedge placed under the door, or by any other known expedient. 115

120 The mountings above described with relation to Figs. 3 to 5 inclusive have been made the subject matter of a divisional application, namely Serial No. 408,969 filed November 22, 1929. 125

I claim:

1. In combination, a motor casing, an electric motor therein having an armature shaft, a hollow bracket carried by the casing and forming an extension thereof, a worm on the 130

armature shaft within said hollow bracket, a shaft extending transversely of the armature shaft and projecting through said bracket, a worm gear on the transverse shaft in mesh with said worm, a tubular member removably secured to said bracket and forming a closure therefor, said bracket and said tubular member closely embracing said worm and worm gear and transverse shaft, the transverse shaft being supported by said bracket at one end and by said tubular member at the other, and diametrically opposed means on the ends of the transverse shaft adapted for connection to a strap to be vibrated.

2. In combination, a motor and a casing therefor, strap vibrating means driven by the motor, a bracket supporting the casing and having a lateral extension and a hook adapted to engage an element of a building, and a clamping device on the bracket to forcibly maintain said extension in hooked relation to such building element, said clamping device being adapted to engage a surface lying substantially the same transverse plane as the hook.

3. In combination, a motor and casing, means driven by the motor and arranged to impart vibrating impulses to a strap, a bracket rigid with the casing and having a hooked member arranged to bear against two non-parallel surfaces of an element of a building, and a clamping device carried by said bracket and arranged to react against the building in a direction opposite the direction of bearing of such hooked member to forcibly maintain the hooked member against the said surfaces of such building element and thereby hold the casing in rigid position.

4. In combination, a motor and casing therefor, means supported by the casing and driven by the motor for imparting vibrating impulses to a strap or the like, a unitary bracket rigid with the casing having a horizontal portion projecting from the casing for resting on a window sill and having a downwardly extending portion adapted for engagement with a ledge adjacent such sill, said bracket having clamping means arranged to force against a window adjacent the sill to cause said downwardly extending portion of the bracket to grip the ledge.

In testimony whereof, I hereunto affix my signature.

JAMES D. COLE.
